UNITED STATES PATENT OFFICE.

JAMES M. McCLELLON, OF EVERETT, MASSACHUSETTS; HAROLD B. McCLELLON AD-
MINISTRATOR OF SAID JAMES M. McCLELLON, DECEASED.

BOILER.

Application filed June 3, 1916, Serial No. 101,610. Renewed August 26, 1925.

To all whom it may concern:

Be it known that I, JAMES M. McCLELLON, a citizen of the United States, and a resident of Everett, county of Middlesex, and Commonwealth of Massachusetts, have invented an Improvement in Boilers, of which the following description, in connection with the accompanying drawings, is a specification, like characters on the drawings representing like parts.

This invention relates to boilers, and among other objects provides an improved fire-box and combustion chamber construction.

15 The boiler shown herein is an improvement upon the one shown in my co-pending application Serial No. 86,857, filed March 27, 1916.

The character of the invention may be best understood by reference to the following description of an embodiment of the invention shown in the accompanying drawings, wherein,

20 Fig. 1 is a view partly in side elevation and partly in vertical, longitudinal section of a boiler shown herein as embodying the invention;

Fig. 2 is a vertical, transverse section taken on line 2—2 of Fig. 1; .

30 Fig. 3 is a horizontal section taken on line 3—3 of Fig. 2; and

Fig. 4 is a horizontal section taken on line 4—4 of Fig. 1.

Referring to the drawings, the illustrative 35 boiler shown therein as embodying the invention comprises a barrel 1 (Figs. 1 and 2) having a flue sheet 3 located a substantial distance forward from the rear end of the barrel to provide a combustion chamber.

40 The usual flues 5 and larger flues 7 to receive the superheating tubes (not shown) are connected to the flue sheet and extend forwardly in the barrel therefrom.

To form the crown of the fire-box and combustion chamber, side drums 9 (Figs. 1 and 2) and a larger intermediate drum 11 are provided preferably extending the length of the fire-box and combustion chamber. The forward ends of the side drums 9 are overlapped by and riveted to side portions 13 (Fig. 1) of the barrel, a top section of the latter above said portions being removed. The forward ends of said drums are open for communication with said barrel and are formed to fit the segment shaped opening be-

tween the upper edge of the flue sheet and the curved upper wall of the barrel, and are riveted to said flue sheet and barrel. The rear ends of said drums may be closed by bumped heads 15 provided with suitable manholes and covers therefor.

At the bottom of the fire-box is a foundation chamber 17 preferably tubular in form, rectangular in section, and extending along the sides and rear end of the fire-box.

To form the sides of the fire-box, series of tubes 19 are provided extending between the foundation chamber and the side crown drums and preferably are curved inward adjacent the latter as shown in Fig. 2.

An important feature of the invention relates to the connection of said tubes with said foundation chamber and drums. To accomplish this the tubes may be divided into groups, two tubes being shown herein in each group, although the number may be varied as required. Each group is provided at its upper end with a header 21 (Figs. 1 and 4) elongated and preferably of rectangular form. The upper end portions of the tubes may be squared to fit said header and may be securely welded or otherwise secured thereto.

The squared end of the tubes fit together like blocks and provide a section or panel of wall formed by the group of tubes with the flat-sided end portion which, viewed from the top, is cambered. The header preferably has an open top receiving the ends of the tubes and filled by them, the sides or flanges of the header over-lapping on the flat sides of the end portion of the group of tubes and fitting thereagainst. The tubes of each group preferably are closely assembled and welded together to form a

tight side closure for the fire-box. Any small spaces at the juncture of the tubes with the header may be closed by fillers welded thereto. To contribute to the strength of the header, the longer sides thereof may be connected by a stay bolt 23, although this is not indispensable.

To connect the headers with the drums the former may be provided with necks 25 pressed therefrom and adapted to be expanded into apertures 27 in said drums.

Each group may have the lower ends of its tubes squared to fit into a header 29 similar to the upper header 21 described. The lower headers may have necks 31 expanded into widely spaced apertures 32 in the upper

wall of the foundation chamber. Plugs 33 are provided in the bottom wall of the foundation chamber opposite the necks 31 to provide convenient access thereto for purposes 5 of cleaning, replacement or repair.

The headers of each group will be common to both tubes thereof and serve to connect the same with the drum and foundation chamber and provide communication therebetween. This enables the apertures in said 10 drum and chamber respectively, to be widely spaced as well shown in Fig. 1, leaving a substantial amount of material between the apertures. This has important advantages, 15 since it enables the drum walls to be of uniform thickness throughout, and the foundation chamber walls to be of uniform thickness throughout, without the necessity of providing extra thickness or reinforcement 20 in the portions thereof surrounding said apertures. Also the connection of the tubes with the drum and chamber may be easily and readily made since merely a small number of apertures are necessary therein and 25 a small number of necks are required for connection with said apertures. The headers may be readily applied to the tubes before they are assembled with the drums and chamber, thereby permitting the connection 30 to be conveniently and readily effected.

At the rear end of the fire-box a tubular wall 35 (Fig. 1) may be provided similar to the one shown in my said co-pending application, and therefore need not be described in detail herein.

Referring now to the combustion chamber, as stated, the crown thereof may be formed by the drums 9 and 11. The side walls thereof are formed by series of tubes 37 having 40 their upper ends connected to and communicating with the side crown drums 9 through headers 38 similar to those described for the tubes 19. These tubes are closely assembled substantially to fill the 45 space between the flue sheet and the rear end of the barrel and may be curved to conform to the contour of the barrel. The lower ends of said tubes terminate adjacent the bottom of the barrel and may be formed to fit and be welded into headers 39 having necks 40 50 (Fig. 1) depending therefrom and expanded into apertures 40^a in the bottom wall of said barrel. The ends of the headers opposite the ends of the tubes may have plugs 41 threaded therein which may be readily removed to furnish access to the ends of said tubes for convenience in assembly, repair 55 and cleaning thereof. Tiles 42 may be placed upon the headers to protect them from the high heats of the gases of combustion from the fire on the grate.

To supply water from the barrel to the bottom headers, a plate 43 (Fig. 3) may be provided formed to provide an ample chamber beneath the combustion chamber. This

chamber may be T-shaped with an end 45 beneath the barrel directly in front of the flue sheet and communicating with said barrel through a series of elongated apertures 47 therein. The plate 43 has a flange 43^a 70 surrounding the same which may be riveted directly to the barrel, thus eliminating the necessity for a separate top wall for the water supply chamber, and providing a simple, compact construction enabling water to 75 pass freely from the barrel to the headers and thence up through the tubes 37. The plate 43 may have vertical stays 49 (Figs. 1 and 3) connecting the same with the bottom of the barrel to strengthen the chamber. 80

To provide communication between said water supply chamber and the foundation chamber referred to, vertical plates 51 and 53 (Fig. 1) are provided beneath the barrel and curved to conform to the contour of the barrel. These plates provide a throat chamber. The plate 51 has a flange 55 extending into the barrel and riveted thereto to protect the edge of said barrel. The forward ends of the side legs of the foundation chamber may be connected to the plate 51 by collars 57 pressed from said plate and riveted to said chamber. The lower ends of said plates may be connected to an intermediate foundation member 61 and they may be strengthened by stays 63 connected thereto. Tie-rods 60 may connect the plate 51 with the forward end of the water supply chamber. 95

Water may freely flow from the barrel through the water supply chamber down through the space between the plates 51 and 53 into the foundation chamber, and rise thence through the side and end wall tubes to the crown chamber.

Elbow pipes 64 (Fig. 2) may allow fluid 105 to escape upward from the space between the plates 51 and 53 to certain of the combustion chamber tubes.

Arch tubes 65 (Fig. 1) may extend from the plate 51 rearwardly and upwardly to 110 the crown drums and support a tile wall 67 for baffling the gases of combustion in their transit from the grate (not shown) to the combustion chamber.

By my invention a fire-box and combustion chamber are provided having strong and simple means to connect the tubes thereof with upper and lower chambers, while permitting a free circulation of fluid there-through.

In the present application I have claimed solely the construction herein shown wherein the wall tubes are arranged in groups or panels. More generic claims covering such construction among others and claims to other features herein disclosed are embodied in my application Serial No. 277,968 filed Feb. 19, 1919 which is a continuation, in part, of the present and of other applications. 125 130

It will be understood that the invention is not limited to the particular embodiment shown herein, but various deviations may be made therefrom without departing from the spirit and scope of the claims.

Claims:—

1. In a boiler, a chamber, a tubular water containing wall comprising tubes set side by side said wall extending longitudinally of the chamber and means for placing said tubes in communication with the interior of said chamber comprising headers each communicating with said chamber and with a group of said tubes.
2. In a boiler, a chamber, a tubular water containing wall comprising tubes set side by side said wall extending longitudinally of the chamber and means for placing said tubes in communication with the interior of said chamber comprising headers having open tops each receiving the ends of a group of said tubes and also having an opening to the interior of the chamber.
3. In a boiler, a chamber, a tubular water containing wall comprising tubes set side by side said wall extending longitudinally of the chamber and means for placing said tubes in communication with the interior of said chamber comprising headers having open tops each receiving the ends of a group of said tubes and having necks entered through the wall of said chamber, the number of tubes being several times greater than the number of such necks.
4. In a boiler, a chamber, a tubular water containing wall comprising tubes set side by side extending longitudinally of the chamber, each tube having a wall of substantially uniform thickness and being substantially circular in section, groups of said

tubes having end portions joined together, headers each having an open top receiving the end portions of a group of tubes and sides extending over and fitting the sides of said end portions and fusedly joined thereto, and means providing communication between the headers and the chamber.

5. In a boiler, in combination, a barrel, a flue sheet therein, means exterior to the barrel shell and in co-operation therewith forming a water chamber extending rearwardly of the flue sheet, a combustion chamber comprising tubes set side by side and housed within said barrel shell, headers each receiving the ends of a group of said tubes and means providing communication through said barrel shell between the interior of said headers and the interior of the chamber.

6. In a boiler, crown and bottom chambers and side walls extending between them each comprising a plurality of sections or panels, each panel comprising a plurality of laterally contacting tubes, corresponding ends of the tubes of each panel fitting a header which extends longitudinally of the chambers and a neck on said header entering the adjacent chamber.

7. In a boiler, crown and bottom chambers and side walls extending between them each comprising a plurality of sections or panels, each panel comprising a plurality of laterally contacting tubes, upper and lower ends of the tubes of each panel fitting respectively into longitudinal headers and necks on said headers entering the adjacent chambers.

In testimony whereof, I have signed my name to this specification.

JAMES M. McCLELLON.
